United States Patent Office.

ELIAS WERDEN, OF PITTSFIELD, MASSACHUSETTS.

Letters Patent No. 93,025, dated July 27, 1869.

IMPROVEMENT IN CLOTHES-RACK.

The Schedule referred to in these Letters Patent and making part of the same.

To all whom it may concern:

Be it known that I, ELIAS WERDEN, of Pittsfield, in the county of Berkshire, and State of Massachusetts, have invented a new and improved Clothes-Rack; and I do hereby declare that the following is a full, clear, and exact description thereof, which will enable others skilled in the art to make and use the same, reference being had to the accompanying drawings, forming a part of this specification, in which—

Figure 1 represents a side elevation, partly in section, of my improved clothes-rack.

Figure 2 is a plan or top view of the same.

Similar letters of reference indicate corresponding parts.

This invention relates to a new clothes-rack, which is of very simple construction, and which can, when not used, be folded together into a small space.

The invention consists in fitting upon four or more or less vertical posts, connecting-rods, which are arranged in sections, horizontally above each other, every section being supported by shoulders of the posts.

A A, in the drawing, are posts, made of wood or other suitable material, each post having two or more shoulders, a a, it being smaller at the upper than on the lower end, as shown.

B B are bars, made of wood or other suitable material, and provided, at suitable distances from their

ends, with circular apertures, which allow them to be fitted upon the posts.

The bars B are fitted in sections upon the posts, to connect the same into a four or more sided frame or otherwise, so that every section is supported on one set of shoulders of the posts.

When each post has but two shoulders, as in fig. 1, there will be but two sections of bars, B, but there may be three or more sets of shoulders, if desired.

Every bar, B, being swivelled, the whole frame is adjustable, and can be folded together or expanded at will.

The bars B are held down upon the shoulders by well-fitting leather washers, c, nuts, keys, or other devices.

Having thus described my invention,

I claim as new, and desire to secure by Letters Patent—

A clothes-rack, consisting of the posts A, which have the shoulders a a, and of the pivoted swinging bars B, which are arranged in sections, substantially as herein shown and described.

The above specification of my invention signed by me, this 23d day of June, 1869.
